UNITED STATES PATENT OFFICE.

JOHN A. MILLIGAN, OF BOSTON, MASSACHUSETTS, ASSIGNOR OF ONE-HALF
TO FRANK F. ENO, OF SAME PLACE.

DESIGN FOR A FLANGED COLLAR.

SPECIFICATION forming part of Design No. 34,031, dated February 5, 1901.

Application filed January 3, 1901. Serial No. 42,025. Term of patent 14 years.

To all whom it may concern:

Be it known that I, JOHN A. MILLIGAN, of Boston, in the county of Suffolk and State of Massachusetts, have invented and produced 5 a new and useful Design for a Flanged Collar for Use Between a Tapered Shaft and the Hub of a Rotary Cutter, of which the following is a specification, reference being had to the accompanying drawings, forming a part thereof. 10 Figure 1 of the drawings shows my new design in perspective. Fig. 2 shows my new design in perspective, viewing it, however, from another point; and Fig. 3 is a section through the body of the collar in the line *x*, Fig. 1. 15 As shown in the drawings, the leading or material feature of my design consists of a collar *a*, cylindrical externally and provided at one end with a flange *b*, the collar showing extended from its smaller end toward the 20 flange-lines *c*, said lines terminating at the inner edge of the flange, other lines *d* showing at the face and edges of the flange and ex-

tended along the collar, as shown in Figs. 2 and 3, toward the small end of the collar, the lines *d* representing slits cut to separate the 25 collar, the cuts going nearly to the smaller end of the collar, while the lines *c* are cut starting from the smaller end of the collar and terminating at the flange. The inner diameter of the collar presents a tapering face, 30 as *e*.

Having fully described my design, what I claim as new, and desire to secure by Letters Patent, is—

The design for a flanged collar, as herein 35 shown and described.

In testimony whereof I have signed my name to this specification in the presence of two subscribing witnesses.

JOHN A. MILLIGAN.
